CLAIM

The ornamental design for a combined illuminable visor
mirror, pen, note pad and index pad, as shown and described.

DESCRIPTION

FIG. 1 is a perspective view of the front, top and one end of
a combined illuminable visor mirror, pen, note pad and
index pad showing my new design;

FIG. 2 is an elevation view of the opposite end thereof;

FIG. 3 is a bottom plan view thereof;

FIG. 4 is a rear elevation view thereof; and,

FIG. 5 is a perspective view of the front, top and one end
thereof with the note pad and index pad in open condition.
